UNITED STATES PATENT OFFICE

PERCIVAL HARRIS, OF ROCKAWAY PARK, NEW YORK

DOLL

Application filed July 23, 1929. Serial No. 380,436.

This invention relates to dolls, and more particularly to dolls' heads bearing eyelashes thereon and to the manufacture of the same.

Dolls of the more expensive kind usually bear eyelashes, but such dolls also are generally equipped with movable eye sets, and the eyelashes are affixed thereto. Dolls of cheaper manufacture ordinarily are merely painted, and do not carry natural hair eyelashes which actually project in a life-like manner from the head of the doll.

My invention relates more particularly to the latter class of dolls, and the primary object thereof resides in the provision of a doll's head having eyelashes directly affixed thereto, and further, in the provision of a method for the manufacture of such dolls which makes it possible to market them at a cost only slightly exceeding that of dolls' heads bearing no eyelashes. To the fulfillment of this object, in accordance with my invention the doll's head is provided with eyelash slits, preferably but not necessarily cut only partially through the wall of the head near the eye portions thereof, and the eyelashes are cemented in these slits.

One specific object of my invention is to simplify the process of cutting the eyelash slits into the wall of the head, and this I do by simultaneously molding the head to the proper configuration and cutting the eyelash slits therein, the mold being initially equipped with cutting tools or projections which serve to impress or mold the desired eyelash slits directly into the wall of the head.

Before applying the coloring to a doll's head made of molded composition it is customary to coat the head with a protective size, which ordinarily is itself tinted to constitute a base color. This operation is apt to clog up the eyelash slits, particularly when, as is desirable, the coating of size is applied by dipping the dolls' heads into a vat of the size. To overcome this objection the method of my invention further includes indenting the coating of size at the eyelash slits, after permitting the size to partially dry, in order to press the size into the slits or recesses. The final formation of the slit should best

be done after coating the head with size, in order to prevent the size from stopping up the slit, but should preferably be done before the size has completely set, in order to prevent cracking and breakage of the size. This not only clears out the slits but also has the advantage of coating the walls of the slits, giving them a relatively finished appearance, so that if through some accident the eyelashes of the doll are subsequently pulled out of the slits the appearance of the head is not marred so seriously as would be the case were these slits left in a raw and unfinished condition.

In accordance with the complete method of my invention the doll's head is put through various process steps, some of which are relatively optional, in order to protect and color it in the desired manner, and finally the eyelashes are cemented into place, either by applying glue to the eyelash slits and thereafter inserting the eyelashes, or more preferably by dipping the base edges of the eyelashes into glue and then inserting the eyelashes into the eyelash slits.

In my copending application, Ser. No. 266,974, filed April 3, 1928, I have disclosed a novel eyelash consisting of a fringe layer of hair strands held together by a foundation or base consisting of fabric strands interwoven with the hair strands at one end thereof, the entire lash being left in a flat and uncemented condition, whereby it may be handled with considerable flexibility and ease, and readily bent and fanned to assume the desired life-like appearance. In that application I have also illustrated the application of such an eyelash to a flexible doll's head or mask, the walls of which are relatively thin and yieldable.

A specific object of the present invention is to apply such an eyelash to relatively thick and rigid dolls' heads of the molded type. To this end it is merely necessary to employ the foregoing or any other suitable method for providing eyelash slits, and the foundation or woven edges of the eyelashes are simply inserted edgewise into these slits and cemented to the walls thereof. The hair strands and the fabric strands of the supporting foundation are both exposed to the

cementing action, and the strands are held between, cemented to, and supported by the walls of the slits. The lash not having been previously cemented, may be fanned into 5 desired formation at the time of its insertion, and there held for an instant until the glue begins to set, whereupon the lash will be permanently fixed and held in the desired shape.

10 To the accomplishment of the foregoing and such other objects as will hereinafter appear, my invention consists in the doll's head and its method of manufacture as herein-after are more particularly described in the 15 specification and sought to be defined in the claims. The specification is accompanied by drawings in which:

Fig. 1 is a longitudinal section taken through the female portion of a mold suitable for the practice of my invention;

20 Fig. 2 is a transverse section taken in the plane of the line 2—2 in Fig. 1;

Fig. 3 illustrates a step in the method of my invention;

25 Fig. 4 shows the doll's head at an intermediate stage of its manufacture;

Fig. 5 is an enlarged view of a woven eyelash;

Fig. 6 illustrates the finished doll's head;

30 Fig. 7 is a fragmentary section through one eye showing the manner in which the eyelash is inserted; and

Fig. 8 is a similar section illustrating the use of upper and lower eyelashes.

35 Considered in its method aspect my invention consists broadly in the manufacture of dolls' heads, such as is shown in Fig. 4, by cutting eyelash slits 2, 2 into the walls thereof, preferably but not necessarily by indenting these slits at the time the doll's head is 40 molded, the latter being accomplished by projections, preferably tool inserts 4, 4, shown in Figs. 1 and 2, affixed to the mold 6 used for shaping the doll's head.

45 Considered in its product aspect the invention consists in the manufacture of molded dolls' heads such as is illustrated in Fig. 6, having eyelashes 10 adjacent the eye portions 12 thereof which project from the wall 50 of the head in a life-like manner. The eyelashes preferably consist of the woven hair and fabric strands, as is illustrated in Fig. 5, so that they may be readily fanned at the time of their insertion, the lashes being inserted directly edgewise into the slits 2 arranged to receive the same, as is best shown in Figs. 7 and 8, no bending or interior cementing of the eyelash to the inner wall inside of the head being necessary.

60 Considering the method of manufacture of the dolls' heads more in detail, the female half 6 of the mold therefor is provided with tool inserts 4 properly disposed to cut eyelash slits, preferably only partially through 65 the wall of the head at the time of its initial

manufacture. The mold may be made by the use of a temporary sand mold having a configuration corresponding to the forward half of the doll's head, into which the steel cutting tools 4 are inserted edge foremost to the desired depth and at the proper location for the eyelash slits. The mold 6 is thereafter cast around the sand mold, preferably out of bronze, and the resulting bronze mold carries away with it and has integrally cast 70 thereinto the cutting tools 4, the edges of which project beyond the inner face of the mold, and are thereby ready to perform the desired cutting, or more properly speaking, 75 molding operation.

80 After this preliminary modification of the female part of the mold for the forward half of the head, which is clearly illustrated in Figs. 1 and 2, the molding operations for the forward and rear halves of the head may 85 be carried out in the usual manner. This is of great manufacturing advantage, for no extra cutting operation is necessitated. I may mention, however, at this point, that my invention includes the manufacture of dolls' 90 heads in accordance with my subsequent teachings, even if the eye slits are cut into the wall of the head by an operation separate from the molding operation.

95 The front and rear halves of the heads are then cemented together, after which the full heads are coated with a preferably colored glue or size, as by dipping the heads into a vat of the size. The size penetrates into the 100 molded composition material of the head, and protects the same against moisture, and forms a smooth hard base for subsequent coloring operations.

105 The size tends to clog up the eyelash slits, and accordingly, the final step in the formation of the slits must take place after the size has been applied to the head. The next step, therefore, in the present method of manufacture is to indent, cut, or clear out these slits. This is preferably done when the size is only 110 partially dry, in order to prevent cracking and breakage of the size, and may be done by supporting the doll's head on a fixture 20, of any suitable character, and depressing a plunger 22 bearing a pair of tools 24, in 115 this case corresponding to the tools 4, 4 used in the mold. These cut into the slits, and incidentally press the glue or size into the same, thereby giving the slits a finished appearance, which is of advantage not only in performing the subsequent operations of inserting the eyelashes, but also because in case the eyelashes are accidentally pulled out of the 120 head of the doll, the appearance thereof is not marred so badly as would be the case if these slits were in a raw and unfinished condition. The doll's head then appears as illustrated in Fig. 4.

125 While the next several steps in the process of doll manufacture are probably variable, 130

I prefer to employ the following procedure. The cheeks of the doll are sprayed to the proper complexion, after which the entire head is sprayed with a celluloid finishing enamel, and finally, if painted hair is to be used, the same is spray-painted on the appropriate area of the head.

When the doll's head has been otherwise completely finished the eyes are next painted, most simply by hand painting with coloring of exceedingly high luster in order to obtain a life-like effect. Finally the eyelashes are inserted in the eyelash slits.

The preferred form of eyelash is illustrated in Fig. 5, and consists of a layer of hair strands 30, interwoven at one end with fabric strands 32, the latter forming a base or foundation, which extends along one edge thereof. As is illustrated by the brackets A and B, the base or foundation A is relatively narrow, this dimension being made larger in the drawings than in practice, in order to more clearly show the weaving of the hair and fabric strands. This eyelash per se is not claimed herein, being claimed in my copending application already mentioned, but is preferably used in the present process because of its many advantages, such as its complete flexibility in all directions, including its ability to be spread out or fanned while lying in its own plane, and also the fact that it presents a narrow base edge which is readily inserted into the eyelash slits, while the base or foundation B permits the cement which holds the last to the walls of the slit to contact with and bind both the hair strands and the fabric threads.

Now, in accordance with the present invention, this, or any other eyelash found suitable, is cemented into the eyelash slits already described. This may be accomplished by carefully applying a bit of glue to the eyelash slits and thereafter inserting the eyelashes therein, but more preferably is accomplished by gripping the eyelashes on the portion A and dipping the base B into a body of cement and thereafter inserting the base into the eyelash slits. When the eyelash is first inserted into the slit it is fanned and held in desired final form, for an instant, till the glue begins to set, whereupon it may be released and will be permanently fixed and held in the desired shape.

A finished doll's head having eyelashes applied above the eye portions thereof is illustrated in Fig. 6, a section through one eye portion thereof being shown in Fig. 7.

If desired it is readily possible to provide the doll with both upper and lower eyelashes, it being necessary merely to cut both upper and lower slits, as by providing the mold, in the first instance, with appropriate cutting tools for cutting slits for both upper and lower eyelashes, and by providing suitable tools for use on the head after the same has

been coated with size and finally to insert eyelashes in all of the resulting slits. A section through the eye portion of a doll, similar to the section of Fig. 7, but showing both upper and lower eyelashes, is given in Fig. 8. 70

The method of my invention, and the many advantages thereof, will in the main be apparent from the foregoing description. It will be obvious to those skilled in this art that the process for forming the eyelash slits, and the mode of applying the eyelashes thereto, constitute a remarkable manufacturing simplification, relative to the prior art. It will also be understood that the resulting doll is life-like in appearance and a great improvement over a similar doll's head which is not provided with eyelashes. 80

It will be apparent that while I have shown and described the method and product of my invention in the preferred form, many changes and modifications may be made without departing from the spirit of the invention, defined in the following claims. 85

I claim:

1. In the manufacture of heads for dolls, the method which includes cutting a slit partially through the wall of the head near the eye portion thereof, and cementing the base of an eye lash in the eye lash slit. 90

2. In the manufacture of heads for dolls, the method which includes molding the head to proper configuration and simultaneously cutting eyelash slits in the wall of the head near the eye portions thereof. 95

3. In the manufacture of heads for dolls, the method which includes molding the head to proper configuration, cutting slits partially through the wall of the head immediately adjacent the eye portions thereof, coating the head with size, permitting the size to partially dry, indenting the coating at the eyelash slits and cementing the base of an eyelash in each of the eyelash slits. 100

4. In the manufacture of heads for dolls, the method which includes molding the head to proper configuration and simultaneously cutting slits partially through the wall of the head immediately adjacent the eye portions thereof, coating the head with size, permitting the size to partially dry, indenting the coating at the eyelash slits in order to press the size into the recesses, and cementing eyelashes in the eyelash slits. 110

5. In the manufacture of heads for dolls, the method which includes molding the forward half of the head to proper configuration and simultaneously cutting slits in the wall of the head immediately adjacent the eye portions thereof, molding the rear half of the head, cementing the halves of the head together, coating the head with size, permitting the size to partially dry, indenting the coating at the eyelash slits, and finally cementing the base of an eyelash in each of the eyelash slits. 120

6. In combination, a doll's head bearing representations of eyes thereon, eyelash slits cut partially through the wall of the head immediately adjacent the eye representations thereof, and eyelashes cemented in said slits.
- 5 7. In combination, a doll's head bearing representations of eyes thereon, slits cut partially through the wall of the head immediately adjacent the eye representations thereof, and eyelashes held in said slits, each of said eyelashes comprising a fringe layer of hair strands and a supporting foundation therefor consisting of a network of fabric strands interwoven with the strands of the hair layer.
- 10 8. In combination, a doll's head bearing representations of eyes thereon, eyelash slits cut partially through the wall of the head immediately adjacent the eye representations thereof, and eyelashes held in said slits, each eyelash comprising a fringe layer of strands held between, cemented to, and supported by the walls of said slit.
- 15 9. In combination, a doll's head bearing representations of eyes thereon, slits cut partially through the wall of the head immediately adjacent the eye representations thereof, and eyelashes held in said slits, each of said eyelashes comprising a fringe layer of hair strands and a supporting foundation therefor, the supporting foundation consisting of a network of fabric strands interwoven with the strands of the hair layer at one end of said layer, and adhesive means securing said eyelash foundation to the walls of said slit.
- 20 10. In the manufacture of molded heads for dolls, the method which includes coating the head with size, forming finished slits in the wall of the head immediately adjacent the eye portions thereof when the size has only partially set, and cementing the base of an eye lash in each of the eye lash slits.
- 25 11. In the manufacture of molded heads for dolls, the method which includes cutting thin slits in the wall of the head immediately adjacent the eye portions thereof, coating the head with size, forming finished slits in the wall of the head when the size has only partially set, and cementing the base of an eye lash in each of the eye lash slits.

Signed at New York, in the county of New York an State of New York, this 17th day of July, A. D. 1929.

PERCIVAL HARRIS.
